UNITED STATES PATENT OFFICE

2,000,578

PYRIDINIUM IODIDES AND PROCESS OF PREPARING THEM

Leslie G. S. Brooker, Rochester, N. Y., assignor
to Eastman Kodak Company, Rochester, N. Y.,
a corporation of New York

No Drawing. Original application January 16, 1933, Serial No. 652,030. Divided and this application November 7, 1933, Serial No. 697,067

6 Claims. (Cl. 260—41)

This invention relates to intermediates used in the preparation of cyanine dyes of the tri-carbocyanine series. These intermediates may be termed (2-quinolyl alkyl iodide)-pyridinium iodides and (2-pyridyl alkyl iodide)-pyridinium iodides. This application is a division of my pending application Serial No. 652,030 filed January 16, 1933.

10 It is an object of my invention, therefore, to provide these new dye intermediates and a method of preparing them.

In general, the method of preparing these intermediates is as follows: Equimolecular proportions of 2-iodoquinoline alkyl iodides and pyridine are caused to combine to give intermediate compounds of a new type, probably represented by the following formula—

(2-quinolyl alkyl iodide)-pyridinium iodide

30 These intermediate compounds can be isolated by treating the finely pulverized 2-iodoquinoline alkyl iodides with pyridine, preferably in the cold, for 12 to 24 hours, and are then obtained
 35 as orange colored solids which can be purified by very rapid recrystallization from water. It is convenient to employ a large excess of pyridine in the reaction. The new compounds are unstable towards recrystallization but are quite
 40 soluble in hot water, whereas the 2-iodoquinoline alkyl iodides are only sparingly soluble. (2-quinolyl methiodide)-pyridinium iodide is obtained as orange-ochre crystals on recrystallization from water and melts at 170-171° C. (with
 45 decomp.) (corr.). The corresponding ethiodide melts at 167-168° (with decomp.) (corr.).

The 2-iodopyridine alkyl iodides, in a similar fashion, give rise to the compounds probably possessing the structural formula

(2-pyridyl alkyl iodide)-pyridinium iodide

These compounds are yellow solids and are recrystallized in the same manner as described in the previous paragraph.

While the methyl and ethyl groups are the alkyl radicals which I commonly employ in the alkyl iodides used as starting materials, it is obvious that I may employ any of the other alkyl radicals commonly known to those skilled in the art.

What I claim as my invention and desire to be secured by Letters Patent of the United States is:

1. (2-quinolyl alkyl iodide)-pyridinium iodide.
2. (2-pyridyl alkyl iodide)-pyridinium iodide.
3. The process which comprises condensing pyridine with a compound of the following structure:

wherein R represents an alkyl group and B represents a substituent selected from the group consisting of vinylene and phenylene. 25

4. The process which comprises condensing pyridine with a 2-iodopyridine alkyl iodide.
  5. The process which comprises condensing pyridine with a 2-idoquinoline alkyl iodide.
  6. A quaternary salt of the following structure:

wherein R represents an alkyl group and A represents a substituent selected from the group consisting of vinylene and phenylene.

LESLIE G. S. BROOKER. 45
